UNITED STATES PATENT OFFICE.

ALFRED W. BRUCE, OF NEW YORK, N. Y.

LOCOMOTIVE.

Application filed January 24, 1924. Serial No. 688,176.

To all whom it may concern:

Be it known that I, ALFRED W. BRUCE, a citizen of the United States, residing at New York, in the county and State of New York, have invented a certain new and useful Improvement in Locomotives, of which improvement the following is a specification.

My invention relates to locomotive engines of the well known "Mallet" type, in which two independent groups of driving wheels are operated by the pistons of separate pairs of cylinders, and its objects are (a), to enable an increase of tractive power 10 to be attained within determined width limits; and, (b), to attain a more even torque of the pistons of the forward cylinders and reduce the liability to slipping of the group of driving wheels actuated by them.

The improvement claimed is hereinafter fully set forth.

In the accompanying drawings: Figure 1 is a diagrammatic side view, in elevation, of a Mallet locomotive engine in which my invention is applied; Fig. 2, a plan or top view of the same, with the boiler removed; and, Figs. 3 and 4, diagrammatic vertical transverse sections, on the lines *a a* and *b b*, respectively, of Fig. 1.

My invention is herein exemplified as applied in a Mallet locomotive, the boiler, 1, of which is, as in prior and present practice, supported on a rear group of eight driving wheels, 2, journalled in bearings 30 in a main frame, 2^a, connected to the boiler without the capacity of relative lateral movement, and on a forward group of driving wheels, 3, journalled in a supplemental frame, 3^a, which is pivotally connected to 35 the main frame, so as to have the capacity of swivelling movement about the axial line of its pivotal connection, relatively thereto. The rear and front groups of driving wheels are, as heretofore, independently connected to, and rotated by, the pistons of separate sets of steam cylinders.

In the practice of my invention, referring descriptively to the specific embodiment thereof which is herein exemplified, 50 steam, from the boiler, 1, is supplied, through valve governed steam supply pipes, 5, 5^a, to the valve chests of a pair of steam cylinders, 4, 4^a, supported on the main frame, 2^a, the pistons of which cylinders 55 are coupled, in the usual manner, to one of the pairs of driving wheels of the rear

group, 2, and steam is exhausted from said cylinders, into the smoke box, 1^a, of the boiler, through exhaust pipes, 4^c, 4^d, and 4^e. The pipes, 4^c and 4^d, extend forwardly, 60 on opposite sides of the boiler, at a greater distance apart than the locomotive frames, and are connected, at their forward ends, to the pipe, 4^e, which leads to an exhaust pipe and nozzle in the smoke box. 65

The wheels of the supplemental frame, 3^a, of the locomotive, are actuated by the pistons of a set of cylinders supported on said frame, and consisting of a middle cylinder, 6, and two side cylinders, 6^a, 6^b. 70 The pistons of the cylinders, 6, 6^a and 6^b, of the supplemental frame, are coupled to crank pins on one of the axles of the driving wheels, 3, of the forward group, and live steam from the boiler is supplied to 75 said cylinders through pipes, 5^{aa} and 5^{bb}, which extend forwardly, in line with the steam supply pipes, 5, 5^a, of the cylinders of the rear group of driving wheels, and are articulated thereto by joints, 5^c, of the 80 ordinary construction.

The steam pipes, 5^{aa} and 5^{bb}, lead into a transverse front channel section, 7^c, which is in continuously open communication with the valve chests, 8, 8^a, and 8^b, of the cylinders, 6, 6^a and 6^b, respectively. As shown 85 in Fig. 3, the channel section, 7^c, is cast integral with the cylinders, 6, 6^a and 6^b, but such specific structural form is not essential, as the channel section may, without departure from my invention, be made as a separate pipe, connecting the steam supply pipe with the valve chests of said cylinders. Steam is exhausted from the cylinders, 6, 6^a and 6^b, through a pipe, 9, 95 leading to an exhaust pipe and nozzle, in the smoke box. A joint, 9^a, is fitted in the exhaust pipe 9.

It will be observed that all the steam pipe lines are located on opposite sides of the boiler, above, and at a greater distance apart than, the locomotive frames, and that, except for their short front sections, the exhaust pipe lines are similarly disposed. By such location, free space is afforded for the installation of the connections of the piston of the middle cylinder, 6, with the crank pin of the axle which it actuates. 100

It will be seen that the following substantial advantages are attained by the application of my invention in a Mallet lo- 105 110

comotive. The more uniform torque and increase of tractive power within determined width limits, which have been proven to be resultant upon the application of three cylinders, in locomotives of other types, have not heretofore been available in Mallet locomotives, by reason of structural conditions, as the space between the side members of the forward supplemental frame, is so materially obstructed as to prevent the installation of the valve operating mechanism of three cylinders, as well as to interfere with the crank axle and main connecting rod of the middle cylinder. My invention, hereinbefore described, being fully exempt from this objection, the application of three cylinders, in connection with either or both groups of wheels of Mallet locomotives, is rendered fully practicable.

While, in the embodiment of my invention which is herein set forth, the driving wheels of the rear group are shown as being rotated by the pistons of two cylinders only, my invention is not limited to such specific construction, as three cylinders may be applied in connection with the driving wheels of said rear group, without departure from the spirit and operative principle of my invention.

I claim as my invention, and desire to secure by Letters Patent:

1. In a locomotive of the Mallet type, the combination of a rear group of driving wheels; a front group of driving wheels; cylinders, the pistons of which actuate the rear group of driving wheels; means for effecting exhaust directly to the atmosphere from said cylinders; three cylinders, the pistons of which actuate the front group of driving wheels; and means for effecting

exhaust to the atmosphere from said cylinders.

2. In a locomotive of the Mallet type, the combination of a rear group of driving wheels; a front group of driving wheels; cylinders, the pistons of which actuate the rear group of driving wheels; three cylinders, the pistons of which actuate the front group of driving wheels; steam supply pipe lines, connecting the valve chests of all the cylinders directly with the boiler, and extending longitudinally on opposite sides of the frame of the cylinders of the rear group; exhaust pipes, located below the steam supply lines and leading directly from the cylinders of the rear group to the atmosphere; and independent exhaust pipes, leading from the cylinders of the front group to the atmosphere.

3. In a locomotive of the Mallet type, the combination of a rear group of driving wheels; a front group of driving wheels; cylinders, the pistons of which actuate the rear group of driving wheels; three cylinders, the pistons of which actuate the front group of driving wheels; exhaust steam pipe lines, connecting the valve chests of the rear cylinders with the smoke box, and comprising two side sections leading forwardly from the valve chests of the rear cylinders and a short central section located between said side section and the forward cylinders; and independent exhaust steam lines, leading from the cylinders of the front and the rear groups, respectively, to the atmosphere.

ALFRED W. BRUCE.
